US00D630996S

(12) **United States Design Patent**
Gall et al.

(10) **Patent No.:** US D630,996 S
(45) **Date of Patent:** ** Jan. 18, 2011

(54) **AIRCRAFT**

(75) Inventors: **Pierre-Emmanuel Gall**, Toulouse (FR);
Julien Ricouard, Toulouse (FR)

(73) Assignee: **Airbus Operations S.A.S.**, Toulouse
Cedex (FR)

(**) Term: **14 Years**

(21) Appl. No.: **29/368,422**

(22) Filed: **Aug. 24, 2010**
